DESIGN FOR AN OIL-CAN BODY.

SPECIFICATION forming part of Design No. 29,622, dated November 8, 1898.

Application filed October 1, 1898. Serial No. 692,439. Term of patent 7 years.

To all whom it may concern:

Be it known that I, CHARLES W. CUMMINGS, a citizen of the United States, residing at Philadelphia, county of Philadelphia, and State of Pennsylvania, have invented and produced a new and original Design for an Oil-Can Body, of which the following is a full, clear, and exact description, reference being had to the accompanying drawings, which form a part of this specification.

The design is for the body of an oil-can; and it consists of the novel configuration of the body.

The body of the can is provided with two series of ribs or grooves extending around the circumference of the can and separated by a plain surface. The upper series of ribs or grooves is inclined somewhat to the vertical in one direction, while the lower series is inclined somewhat to the vertical in the opposite direction. As shown, there is also a plain surface of slight vertical height around the circumference of the body just above and adjacent to the base. The plain surface separating the series of ribs or grooves is also shown as on the same plane with the top of the ribs, while the grooves are pressed in or sunk beneath the surface of the body. 25

Having now fully described my invention, what I claim, and desire to protect by Letters Patent, is—

The design for the body of an oil-can substantially as shown and described. 30

In testimony of which invention I have hereunto set my hand, at Philadelphia, on this 29th day of September, 1898.

CHARLES W. CUMMINGS.
